UNITED STATES PATENT OFFICE.

GEORGE E. JOHNSON, OF FORT WAYNE, INDIANA.

DESIGN FOR A CUSPIDOR-BOWL.

SPECIFICATION forming part of Design No. 32,287, dated February 27, 1900.

Application filed December 9, 1899. Serial No. 739,855. Term of patent 14 years.

To all whom it may concern:

Be it known that I, GEORGE E. JOHNSON, a citizen of the United States, residing at Fort Wayne, in the county of Allen, in the State 5 of Indiana, have invented certain new and useful Improvements in Designs for Cuspidor-Bowls; and I do hereby declare that the following is a full, clear, and exact description of the invention, which will enable others skilled in the art to which it appertains to make and use the same, reference being had to the accompanying drawings, which form part of this specification.

My present invention relates to new and 5 original designs for self-cleansing dental-cuspidor bowls.

In the accompanying drawings, illustrating my invention, similar reference-numerals indicate like parts throughout the several views, o in which—

Figure 1 is a front elevation of a dental-cuspidor bowl, showing my new and original design. Fig. 2 is a side elevation of the same. Fig. 3 is a bottom perspective of the same 5 looking from the front, and Fig. 4 is a bottom perspective looking from the rear. Fig. 5 is a top plan of the same, showing the corrugated perimeter, the contour of the concave bottom, and the location of the discharge- o openings.

As illustrated by the drawings, the leading, vital, and material feature of my design resides in the general contour of the bowl with its corrugated periphery and external 5 surface, presenting the general appearance of one section or half of a bivalved sea-shell with a series of drainage-openings near the

point at which the hinged connection with its companion or complementary section is made.

The bowl exhibiting my design is shallow 40 and slightly elongated, as shown in Fig. 5, and has a band of peripheral convex corrugations 1 nearly encircling the same, the upper portions 2 of which form a somewhat-irregular corrugated upper edge, as shown in 45 Figs. 1 and 5. Instead of the said corrugations 1 the rear face 3 of the bowl is concavo-convex, but slightly corrugated, and is provided with an inwardly - protruding and slightly-overhanging edge 4.

The lower external face or bottom 5 of the bowl is provided with a series of forwardly-extending and divergent corrugations 6, emanating from a point on the said overhanging edge 4, as shown. These divergent corruga- 55 tions are formed into more or less irregular bands 7, which approximate to the arcs of circles of varying centers.

The interior surface of the bowl formed by the upright flange 8 and the concave bottom 60 9 is perfectly smooth.

Having thus described my invention, what I claim as new, and desire to secure by Letters Patent, is—

The design for a cuspidor-bowl, as herein 65 shown and described.

Signed by me at Fort Wayne, Allen county, State of Indiana, this 27th day of November, A. D. 1899.

GEORGE E. JOHNSON.
